UNITED STATES PATENT OFFICE.

WILLIAM H. SAWYER, OF PROVIDENCE, RHODE ISLAND, ASSIGNOR OF
ONE-HALF TO EUGENE F. PHILLIPS, OF SAME PLACE.

ELECTRIC ANNUNCIATOR.

SPECIFICATION forming part of Letters Patent No. 242,055, dated May 24, 1881.

Application filed January 17, 1881. (No model.)

To all whom it may concern:

Be it known that I, WILLIAM H. SAWYER, a citizen of the United States, residing at Providence, in the county of Providence and State of Rhode Island, have invented certain new and useful Improvements in Electric Annunciators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to that class of electric annunciators in which a drop held up by suitable devices is tripped through the instrumentality of an electro-magnet and allowed to fall by gravity. Its objects are to prevent the drop from being thrown down by jarring, currents of air, rebounding, or otherwise unintentionally, while at the same time rendering it readily responsive to its operating electro-magnet, and to render an annunciator capable of being readily adapted to use with either a closed or open circuit.

In the accompanying drawings, Figure 1 is a front view of a single drop, armature, and magnet face-plate in an annunciator constructed according to my invention on the open-circuit plan, the drop being up. Fig. 2 is a similar view with the drop down. Fig. 3 is a view, mainly in section, in a plane coincident with the vertical diameter of the operating electro-magnet.

The annunciator constructed as in the figures above described is especially designed for use in connection with magneto-electric generators, such as are employed in telephone call-systems.

Fig. 4 is a partially-sectional view, illustrating the apparatus organized for use with a closed circuit. Fig. 5 is a partially-sectional view of a modified form of a closed-circuit annunciator.

Referring first to Fig. 3, the letter A indicates an electro-magnet, the front head-piece, A', of the coil of which has a greater diameter than the coil and the circular aperture in the face-board B, in which the magnet is arranged,

and serves as a face-plate for attachment to the front of said board, to hold the magnet and its co-operative devices in position, the margin of said face-plate extending outward beyond the edge of the aperture, as shown in Fig. 4, and having the attaching-screws passed through it and into the board.

Above the magnet, in Figs. 1, 2, and 3, a bifurcated lug, C, is screwed into the face-plate A', and has pivoted to its arms, at their outer sides, the ears d of an armature, D, and by the same pivot-pins are held the ears e of a drop, E, which has upon its back surface a suitable number, letter, or other sign. From said back surface also projects an iron or steel lug, e', which, when the drop is raised, as shown in Figs. 1 and 3, rests upon the head of a magnetized pin, F, which is driven into the board B, the magnetic attraction of this pin serving to hold the drop against being thrown down by jarring, currents of air, or rebound when thrown up.

From the upper edge of the armature B a pin, G, having an eccentric head, extends upward behind the drop E in its elevated position, and when an electric current is passed through the helix of magnet A the armature is attracted by the core a, the head of the pin G strikes the drop, forcing it loose from the hold of the magnetic pin F, and outward beyond its center of gravity, so that said drop falls to the position in which it is shown in Fig. 2, exposing its indicating-face.

In order to utilize both poles of the electro-magnet, I connect the rear end of the core a by means of a metal yoke-piece with a rod, C', which has its front end tapped into the screw-shank of the bifurcated lug C.

When the drop of an annunciator falls it is desirable that a signal should be sounded, and this is usually accomplished by closing a local circuit including an electric bell. I have provided for closing such a signal-circuit by inserting in the armature D a metal screw, D', which passes through it and projects from its rear face sufficiently to come in contact with the head of a metal screw, d', inserted in the face-plate A' when the armature is attracted, thus making a metallic contact which closes the local or signal circuit. I connect with this

screw d' the end of a wire, b , which forms one terminal of the signal-circuit, the other terminal, b' , of which I connect to the rod C' , which brings it into electric connection with the armature through the lug C . Whenever the 5 armature is attracted by the core a , and screw D' strikes d' , the local or signal circuit will, of course, be closed, and a suitable bell may be thus sounded.

10 The magnet A is to be connected with a main circuit and circuit-closing devices in the usual manner.

The apparatus as now described is, as is obvious, arranged for use in an open circuit, and 15 I will now proceed, referring to Fig. 4, to describe how it may be arranged for use in a closed circuit.

In the first place the drop E is to be removed, a suitable inscription having been placed upon 20 the back of the armature. The position of the face-plate A' is then reversed, turning the magnet and bringing the lug C below instead of above the core a . The screw D' is removed from the armature and screwed into a hole 25 which will be noticed in the front end of the core in Fig. 3. The curved pin G is removed from the edge of the armature, its screw end passed through the hole left open in the armature by the removal of screw D' , and screwed 30 into an oblique screw-hole or countersink, which will be noticed in the screw d' in Fig. 1, the pin being left curving downward, as shown in Fig. 4. The magnetic pin F may be removed, as it is of no use in this arrangement.

35 Two parts only, it will be observed, are discarded in arranging the annunciator for a closed circuit, and no new parts are required.

As the parts are now arranged in Fig. 4, if the main circuit, which includes the magnet 40 A , is broken, the armature D , being held outward beyond its center of gravity by the pin D' , will swing downward until it strikes the head of pin G , which stops it in the position shown in dotted lines, in which position its indicating-face is exposed, and at the same 45 time the head of the pin forms an electric contact, which closes the local or signal circuit over the pin, armature, lug C , rod C' , screw d' , and wires b and b' . The magnet A is in this 50 arrangement included in a main circuit having suitable circuit-breakers.

In the modification shown in Fig. 5, which is also adapted for use in a closed circuit, the drop E' is used and provided with a projecting pin, E'' , which comes in contact with the core of an electro-magnet, A'' , when the drop falls, and thus closes a signal-circuit, over said core and a wire, b^2 , connected to its rear end, and over the drop, which is metallic, 55 the lug C^2 , to which it is pivoted, and a wire, b^3 . The armature D^2 is arranged facing the rear end of the core of the magnet A'' , and is

carried by a bent lever, H , which is retracted by a spring, I , and has its outward movement limited by a stop-pin, h , projecting from the 65 face-board B . The outer end portion of the lever H is secured to a short arm, K , which is pivoted to the lug C^2 , and the tip of said lever stands very close to, and may even touch, the drop when the latter is raised and the circuit 70 is closed. The moment the circuit is broken the armature D^2 is released by the core of the magnet, the lever H is drawn upward by the spring I , and its tip thrown forward, forcing the drop away from the magnet F and outward beyond its center of gravity, when it falls to the position shown in dotted lines, exposing 75 its indicating-face and bringing the pin E'' in contact with the core of the magnet to close the signal-circuit, as before described. 80

Having now fully described my invention, and fully explained the operation thereof, I claim—

1. An open-circuit electric annunciator in which an indicating-drop is held in its upright 85 position by a permanent magnet, substantially as described, whereby is obviated the throwing down of the drop by jarring, currents of air, rebounding, or other unintentional agencies. 90

2. The combination, with the electro-magnet A , of the pendent armature D , provided with pin G , the pivoted drop E , and the magnetic pin F , substantially as and for the purpose set forth. 95

3. The combination, with the electro-magnet A , of the pendent pivoted armature D , provided with the removable screw D' , the screw or contact-piece d' , having wire b connected thereto, the wire b' , electrically connected with the said armature, a drop, and a suitable intermediate device for throwing down said drop when the armature is attracted by the core of the magnet, whereby the annunciator may be arranged for the closing of a signal-circuit simultaneously with the falling of the drop, essentially as set forth. 100 105

4. In an electric annunciator, the electro-magnet A , having the screw-socket in the front end of its core, the face-plate A' , adapted for reversal in position, and provided with the lug C , the screw d' , having the screw-threaded socket or countersink, and the armature D , having the removable screw D' , and the removable pin G , whereby the annunciator may 110 be arranged for operation by either a closed or open circuit, essentially as set forth. 115

In testimony whereof I affix my signature in presence of two witnesses.

WILLIAM H. SAWYER.
